UNITED STATES PATENT OFFICE.

WILLIAM E. UPSON, OF LOCKPORT, NEW YORK.

TELEPHONE WRITING-TABLET.

1,291,281.

Specification of Letters Patent.

Patented Jan. 14, 1919.

Application filed January 25, 1915. Serial No. 4,281.

To all whom it may concern:

Be it known that I, WILLIAM E. UPSON, a citizen of the United States, residing at Lockport, in the county of Niagara and State of New York, have invented certain new and useful Improvements in Telephone Writing-Tablets, of which the following is a specification.

My invention relates to a telephone writing tablet, and more particularly to a tablet adapted for attachment to what is generally termed a desk telephone.

The object of my invention is the provision of an attachment for telephones of this type whereby a roll of paper may be carried by the attachment and drawn over a support or table provided with means for severing portions of the paper having memorandum or notations thereon.

Another object of my invention is the provision of a tablet of simple construction, which is inexpensive and durable and which can be quickly attached to the pedestal of a telephone and be retained thereon without in any manner offering inconvenience in the use of the telephone.

The invention consists in the novel features of construction and in the arrangement and combination of parts to be herein-after described and particularly pointed out in the subjoined claims.

In the drawings,—

Figure 1 is a perspective view of a desk telephone having my improved telephone tablet attached thereto.

Fig. 2 is a plan view of the tablet showing the pedestal of the telephone to which it is attached in cross section.

Fig. 3 is a transverse section taken on line 3—3, Fig. 2.

Fig. 4 is a transverse section taken on line 4—4, Fig. 2.

Fig. 5 is a detached perspective view of the index device associated with the tablet, with parts broken away.

Referring now to the drawings in detail, like numerals of reference refer to like parts in the several figures.

The reference numeral 6 designates what is generally termed a desk telephone of which a pedestal or stand forms a part, and 7 designates my improved memorandum tablet adapted for attachment to the pedestal of the telephone. The tablet proper is stamped from a piece of tin or sheet metal

and comprises a flat desk portion 8 having depending flanges 9 at opposite marginal portions, said flanges being extended beyond one end of said desk portion in the form of curved arms 10. The outer ends of these arms are provided with upwardly and rearwardly opening notches 11 which receive a spindle 12 provided with notches 13 near opposite ends into which the arms 12 fit so that lengthwise movement of the spindle is prevented, said spindle lying in the plane of the top surface of said desk portion.

Secured to one end of the spindle is a circular casing 14 in which a cord 15 is yielding held, said cord being secured to a spring-wound object similar to eye-glass cords used as guards, and this cord has a pencil 16 fastened thereto so that upon drawing the cord outwardly, the necessary length is exposed to permit of making notation of conversations had over the telephone.

The desk portion 8 of the tablet has two pairs of transverse incisions formed therein, between each pair of which the metal is stamped upwardly into a plane above the upper surface of said desk portion, as at 17, thus providing paper grooves underneath these upwardly stamped portions through which the paper may be passed, and with this object in view a roll of paper 18 is rotatably mounted upon the spindle 12, with a portion of the paper guided underneath the upwardly stamped portions 17, which may be said to serve as guide members for the paper. The lower guide member 17 also serves as a paper cutter so that after making notations on the paper between the two guide members, the paper may be drawn outwardly until the notations reach beyond the lower guide member, when the paper can be severed by drawing upwardly and laterally on the loose portion of the paper along the lower edge of the lower guide member. This leaves an unused portion of the paper exposed on the tablet for further notations.

By reason of the notches 13 opening upwardly and rearwardly and the spindle lying within said notches in the plane of the top surface of the desk portion 8 of said tablet, the unrolled portion of the paper may be taken hold of and drawn forwardly at all times irrespective of the amount of paper remaining in rolled condition without the possibility of the roll becoming loosened from its supporting arms. Moreover, rolls

of paper may be quickly placed in position on the tablet, and when consumed the usual paper sleeve or core of the roll remaining after consuming the paper may be quickly 5 and conveniently removed.

39 designates a U-shaped securing clip which straddles the pedestal of the telephone and extends through alined openings 19 in the opposite flanges 9 of the tablet, the 10 extremities of said U-shaped clip being threaded and extending outwardly beyond the outer flange 9 and having nuts 20 threaded thereon, said nuts being preferably thumb nuts so that the tablet can be easily 15 removed from a telephone and again applied when desired.

In order that the flanges are not drawn toward each other when tightening the nuts 20, spacing sleeves 21 are placed between 20 said flanges through which parallel members of said U-shaped clip are passed. This also greatly stiffens the tablet so that a certain amount of pressure can be applied thereto while making notations on the paper passing 25 thereover.

It is to be noted that the depending flanges 9 are each provided with a depending lug 40, these lugs being directly opposite and having a pair of the alined openings 19 formed therein. Broadly considered, these depending lugs 40 form part of the flanges 19, and by arranging a pair of openings 19 in the flanges 7 through these lugs and a pair of openings 19 a distance forward of these 35 lugs, one pair is spaced a greater distance from the top of the desk portion 8 than the other, and when the U-shaped securing clip 39 is passed through the two pairs of openings and embraces the pedestal of the telephone, the desk portion is inclined while the 40 securing clip is in horizontal position, in which position it most effectively serves to secure the tablet to the pedestal of the telephone.

45 22 designates an index device on which the names of parties may be written who are frequently spoken to over the telephone. Said index device comprises a casing 23 having a top wall 24, a bottom wall 25, and 50 three edge walls 26, 27, 28. The casing thus constructed has one edge portion open and in the casing arranged to be drawn out of said open side are index cards or sheets 29 which are attached to the casing near one corner 55 thereof by means of a pivot 30, and the successive pages or leaves are spaced apart by separators 31. Secured to the exterior of the casing by means of the pivot 30 is a spring-retained card guard 32, said guard 60 having two members 33, 34, lying respectively against the upper and lower walls of the casing and having their outer ends connected by a cross member 35. Surrounding the pivot 30 is a spring 36, one end of which 65 is secured to one wall of the casing and its

other end to the card guard, as at 37, the cards or sheets 29 and the separators therebetween having their pivot openings of a size sufficiently large to receive said spring. Each of the cards or sheets has finger and 70 index tabs 38 by means of which they may be drawn outwardly to expose the name and telephone number of the party desired, such names being arranged according to alphabet noted upon said tabs. 75

The casing 23 is soldered or otherwise fastened to the flanges 9 of the tablet. Upon drawing a card or sheet out of the casing 23, the guard 32 is compelled to swing on the pivot 30 against the action of the coil spring 80 34, and upon releasing said card or sheet the spring compels the guard, which is in contact with the card, to force said card inwardly into the casing.

The separators 31 are formed of strips of 85 metal arranged diagonally from one corner of the casing to another, as best shown in Fig. 5. In this manner the leaves are separated from one another throughout their greatest length and freedom in action is 90 therefore assured, there being no possibility of the edge of one leaf coming in contact with the edge or tab of another.

Having thus described my invention, what I claim is, 95

1. A telephone tablet having a flat desk portion provided with longitudinal depending flanges having portions extending beyond one end of said desk portion to provide a pair of arms, said arms being notched at their outer ends, a spindle also notched near opposite ends and having its notched portions fitted into the notched outer ends of said arms to prevent lengthwise movement of said spindle, a roll of paper mounted 100 on said spindle adapted to be unrolled over said desk portion, means to retain said unrolled portion flat against said desk portion, and means to secure said desk portion to the 105 pedestal of a telephone. 110

2. A telephone tablet adapted to be secured to the pedestal of a desk telephone and having a flat desk portion provided with longitudinal depending flanges having portions extending beyond one end of said desk portion to provide a pair of arms, said flanges having two pairs of alined openings with the pair of openings nearer said arms a greater distance from the top surface of 115 said desk portion than the other pair, a spindle carried by said arms, a roll of paper mounted on said spindle and adapted to be unrolled over said desk portion, a U-shaped 120 clip adapted to embrace the pedestal of the telephone and passed through said two pairs of alined openings, and nuts threaded onto the ends of said U-shaped clip. 125

3. A telephone tablet having a flat desk portion provided with longitudinal depending flanges having portions extending be- 130

yond one end of said desk portion to provide a pair of arms, a spindle carried by said arms, a roll of paper mounted on said spindle adapted to be unrolled over said desk portion, means at opposite ends of said desk portion to retain said unrolled portion flat against said desk portion, and means to secure said desk portion to the pedestal of a

telephone and so that said desk portion is inclined to the horizontal. 10

In testimony whereof I affix my signature in presence of two witnesses.
